US00D965178S

(12) **United States Design Patent** (10) **Patent No.:** **US D965,178 S**
Rathnam (45) **Date of Patent:** **** Sep. 27, 2022**

(54) **MODULAR POOL WITH COVER**

(71) Applicant: **Modpro Containers Limited**,
Abbotsford (CA)

CA 30075 12/1967
CA 30519 4/1968

(Continued)

(72) Inventor: **Paul J. Rathnam**, Abbotsford (CA)

(73) Assignee: **Modpro Containers Limited**,
Abbotsford (CA)

(**) Term: **15 Years**

(21) Appl. No.: **29/691,999**

(22) Filed: **May 21, 2019**

Related U.S. Application Data

(62) Division of application No. 29/646,803, filed on May 7, 2018, now Pat. No. Des. 864,416.

CLAIM

The ornamental design for a modular pool with cover, as shown and described.

DESCRIPTION

FIG. 1 is a first perspective view of a modular pool with cover showing the design, with the cover in the fully closed position;

FIG. 2 is a second perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a perspective view thereof with the cover in a partially closed position.

The portions of the modular pool with cover shown in broken lines form no part of the claimed design. The length of the cover forms no part of the claimed design.

1 Claim, 7 Drawing Sheets
